Primary Examiner—Janice E. Seeger*Attorney, Agent, or Firm*—Willian Brinks Hofer Gilson & Lione[57] **CLAIM**

The ornamental design for a backrest, as shown and described.

DESCRIPTION

FIG. 1 is a top front perspective view of a backrest showing my new design;

FIG. 2 is a right side elevational view thereof; the left side being a mirror image of the right side;

FIG. 3 is a front elevational view thereof;

FIG. 4 is a rear elevational view thereof;

FIG. 5 is a top plan view thereof; and,

FIG. 6 is a bottom plan view thereof.

The broken lines are for environmental purposes only and form no part of the claimed invention.
